UNITED STATES PATENT OFFICE.

GEORGE L. PUTNAM, OF MOUNT VERNON, NEW YORK.

RAILWAY METALLIC CROSS-TIE AND TROUGH.

SPECIFICATION forming part of Letters Patent No. 285,842, dated October 2, 1883.

Application filed February 6, 1883. (No model.)

To all whom it may concern:

Be it known that I, GEORGE L. PUTNAM, of Mount Vernon, in the county of Westchester and State of New York, have invented a new and useful Improvement in Railway Metallic Cross-Ties and Trough, of which the following is a specification.

The object of my invention is to provide a railway cross-tie, made of metal, whose shape 10 will admit of its being used in connection with a trough for the purpose of supplying water to the tank of a locomotive, as will be herein-after more fully explained.

The shape of my improved tie and the means 15 by which I secure it to the rails and also the trough are fully illustrated in the accompanying drawings, in which—

Figure 1 illustrates a perspective view of the tie having secured to it the rails *a a'* and the 20 trough *A*. Fig. 2 is a transverse section, through the line *x x'*, Fig. 1, showing the manner of securing the rails to the tie by means of the clips *c* and bolts *e*. Fig. 3 illustrates my improved tie constructed to be used without 25 the trough *A*, so that, should it become necessary to lengthen out a trough or insert an additional one at any location on the road, it could be done by simply cutting out the strip *m*.

The clips *o* are usually cast or constructed 30 with the tie, and are preferably made so that one will rest against the inside of the rail and the other against the outside of the opposite rail, so that the tie can be slid out endwise when it becomes necessary to insert a new one. 35 When the tie is used with the trough, it is best to use it without the permanent clips, as the trough will not very well admit of their use. The tie in this case must be slid under the trough and then brought up in position 40 under the rails. It is therefore best to use the adjustable clips *c* both on the inside and outside of the rails.

The shape of my improved tie is illustrated in Fig. 1. The flange *b* on the bottom is in-

tended to act as an anchorage to hold the tie 45 in position, and the flange *d* is to give it bearing-surface and prevent its sinking. The flange *h* is to give the proper bearing-surface to the trough.

The trough *A* is composed of iron or any 50 suitable material, made water-tight. It is of about the shape herein illustrated, and usually made about one-fourth of a mile in length. Thus, by the aid of a chute, the engineer of a passing locomotive is enabled to fill the locomotive-tank with water without stopping his engine. A serious objection heretofore to the use of a trough of this kind has been that, in order to place the trough in a position between the tracks, it often became necessary 60 to cut the tie in two parts, thus leaving no protection against the spreading of the rails.

The principal feature of my invention, therefore, is to combine with the trough *A* a metallic tie which is provided with the necessary 65 depression in its top side to form a seat for the trough.

Having thus described my invention, what I 70 claim as new, and desire to secure by Letters Patent, is—

1. A railway metallic cross-tie provided with a depression in its upper surface, in combination with the trough *A*, for the purpose herein described and specified.

2. A railway metallic cross-tie provided 75 with a depression in its upper side to receive the trough, the flanges *b d* and *h* and clips *c* and bolts *e*, for holding the rails in position, all as described and specified.

In testimony that I claim the foregoing improvement in railway metallic cross-ties and trough, as above described, I have hereunto set my hand this 3d day of February, 1883.

GEORGE L. PUTNAM.
